(57) **CLAIM**

The ornamental design for chair, as shown and described.

DESCRIPTION

FIG. 1 is a left side perspective view of a chair showing an embodiment of our new design and taken from the front;

FIG. 2 is a left side elevation view of the chair shown in FIG. 1; the right side elevation view (not shown) being a mirror image of FIG. 2;

FIG. 3 is a front elevation view of the chair shown in FIG. 1

FIG. 4 is a top plan view of the chair of FIG. 1;

FIG. 5 is a rear elevation view of the chair of FIG. 1; and,

FIG. 6 is a bottom plan view of the chair of FIG. 1.

The fragmented crosshatching shown on the seat and backrest member is understood to be continuous throughout the circumscribed areas.
